X-RAY RADIATION PROTECTIVE SHIELD

Alfred Maier, 12B Schnitzschulstrasse, 8100 Garmisch-Partenkirchen, Germany

Filed Jan. 18, 1974, Ser. No. 434,554

Term of patent 14 years

Int. Cl. D24—99; D29—02
U.S. Cl. D83—1 H

FIG. 2

FIG. 1

FIG. 1 is a top view in perspective of an X-ray radiation protective shield according to the invention consisting of a shield plate and holder; and

FIG. 2 is a bottom view in perspective of the aforesaid shield and holder with the latter affixed to the underside of the shield.

I claim:

The ornamental design for an X-ray radiation protective shield, as shown.
